Filed Oct. 4, 1957, Ser. No. 688,243

Claims priority, application Great Britain May 1, 1957
6 Claims. (Cl. 340—227)

This invention relates to apparatus for giving a signal when there is a sudden high rate of change in temperature in, or in the vicinity of, a power unit or other unit susceptible to variations in temperature and is, for example, useful in aircraft for giving a warning to the pilot or crew in the event of fire or an abnormal rise in temperature occurring. In Patent No. 2,589,869 there is proposed electrically operated apparatus for bringing into operation, by reason of a sudden increase of temperature at a control source, a warning or other electrically actuated device, and which comprises a very sensitive relay operable by a low E.M.F. an electrically operated warning or other electrically operated device operated from a source of electrical energy having a much greater output than said low E.M.F. a holding circuit for the said device, normally inoperative means controlled by the actuation of said relay to connect said electrically operated warning or other device effectively to the said higher E.M.F. source whilst transferring the electrical load from said relay to said holding circuit, a test circuit with means to bring it selectively into operation, and means adapted upon bringing in the test circuit to introduce into the circuit of the said low E.M.F. producing means, an E.M.F. substantially equal to the operative output of the said latter circuit.

For the purpose of obtaining the said low E.M.F. to initiate the operation of the warning apparatus it is preferred to distribute in known manner thermo-couples about the power unit at a plurality of vulnerable points, such thermo-couples being connected to a single warning apparatus and being adapted on actuation, either independently of each other or collectively, to develop the low E.M.F. designed to initiate the operation of the electrically operated warning apparatus as soon as there is a distinct sudden rise in temperature as opposed to a smooth progressive rise at or below the predetermined rate. Thus it was suggested that a plurality of thermo-couples should be connected in series and that each thermo-couple should have one junction exposed to the immediate ambient temperature conditions but that the other junction should be slightly shielded from such ambient temperature. This results in a slow rate of temperature increase heating both junctions simultaneously so that there is no E.M.F. developed whereas a sudden increase due to abnormal conditions such as fire will heat the exposed junctions more rapidly and thus produce an E.M.F.

Thus from the foregoing it will be appreciated that in Patent No. 2,589,869 a number of relays produce a pulsing circuit to obviate the objections aforesaid. However, arising from further experiments we have now introduced an apparatus for giving a signal for the purpose mentioned which, whilst being appropriate to automatic resetting, obviates during normal conditions of the apparatus the necessity of relying on continuous wiping or regular making and breaking of the contacts of the sensitive relay whilst employing two contacts alternately engaged by the contact which is displaced for bringing the apparatus into and out of operation and in pursuance thereof according to the present invention electrically operated means is provided by which the latter mentioned contact is normally maintained clear of the two fixed

2

contacts which are regarded as essential for automatic resetting.

Further in accordance with the present invention fire warning apparatus employing a sensitive two-coil relay, such as e.g. described in the aforesaid patent embodying two contacts engaged individually by a contact movable in reference to a signal to engage one of the said two contacts to make the warning circuit and returned into engagement with the other of the said two contacts when said signal ends so as automatically to reset the apparatus, is characterised in that means is provided which, following automatic resetting of the apparatus separates and maintains constantly separated pending the introduction of a signal to bring the apparatus into operation, the contacts of the sensitive two-coil relay. In effect this amounts to locating the moving contact which responds to the said signal in a normal position which is clear of either of the two contacts with which such moving contact cooperates in the bringing into and out of operation the warning means.

The aforesaid positioning and maintenance of the moving contact into a normal "free" or entirely off position has the advantage that substantial weight is saved as special condensers to suppress radio interference are now unnecessary, and, also arising therefrom "wiping" of the contacts to maintain them clean is now only effected during the very short periods when the moving contact is in engagement with either of the fixed contacts thereby obviating the necessity of a pulsing relay or self interrupting circuits for producing the intermittent making and breaking of the said movable contact and one of the said other contacts.

Still further in accordance with the present invention apparatus for giving a signal of a sudden change in temperature in, or in the vicinity of, a power unit or other apparatus comprises a sensitive two-coil relay having one "movable" contact engageable with one of two other contacts depending on the direction of the current flowing through the coils, a first coil of the two-coils of the relay being connected to a control force, whilst the circuit is provided through the other, i.e. the second coil of the relay and which circuit is a normal inoperative warning circuit adapted to be made operative on engagement of said moving contact with the appropriate one of said two other contacts and held independently of said relay, this latter or "warning on" circuit including electrically energised means energised as the result of the closing of such circuit and serving to bring into position ready for engagement by the moving contact of the sensitive two-coil relay the other one of said two other contacts which, when engaged by the "movable" contact, shorts out the "warning" circuit thereby also de-energising the said means and returning the contact displaceable by the said means to an idle or "free" position clear of the said "movable" contact. "Movable" designates the contact which is actuated in receiving a warning signal.

Embodiments of the invention are illustrated by the accompanying drawings in which FIGURE 1 is a circuit diagram and,

FIGURE 2 illustrates a suitable form of miniature solenoid for actuating the displaceable one of the two contacts which are engaged by the swinging contact of the aforesaid sensitive two coil relay.

Referring to the circuit illustrated in FIGURE 1, a control source CS, which conveniently comprises a plurality of thermo-couples, introduces the very low E.M.F. which initiates the operation of the apparatus for bringing in a warning signal and immediately following such initiation the warning signal is maintained on by means which is energised from a normal source, e.g. a 24 volt source as used in aircraft, the negative and positive leads

of which are indicated by the reference numerals 1 and 2 respectively. The control source CS is connected across the operating coil MR1 of the sensitive two-coil miniature relay which is adapted to operate for very low E.M.F., i.e. a few millivolts through a test button T normally closing contacts 19 and 21 so that at this condition the test button is in parallel with a low resistance R1 (conveniently 1 ohm), in series with the control source CS and the relay coil MR1 which is the initiating or first operating coil of a miniature relay designed to respond to the few millivolts received from the control source CS, the other coil of this miniature relay being indicated by the reference MR2. The moving contact of this miniature relay is indicated by the reference numeral 10. The miniature relay is thus desirably similar in construction to that normally associated with delicate galvanometers, that is to say in which the direction of the current flows through the relay coils has an effect upon the direction in

5 a resistor R7 (about 1,500 ohms) to provide a knock-off current between contacts 10 and 12 after warning operation to prevent sticking of the contacts. The normally closed condition of the change-over contact 15 (i.e. that shown in FIGURE 1), i.e. when in the position when the apparatus is not operating the warning device 18, serves to join the condenser C, via leads 5, 6 and 7 across a resistor R6 (400 ohms) to ensure that the condenser C will be fully discharged in order to allow maximum displacement current to flow through itself when required on operation.

10 The reset or bottom contact 20 of the millivolt relay is attached to the plunger of the solenoid S and also via the lead 9 to the main negative lead 1. It is therefore apparent that when master relay M has operated and the reset contact 20 is displaced by operation of the solenoid S, then upon the moving contact 10 engaging contact 20 due to a reduction in output from source CS,

15 which the moving contact 10 is urged, one of the coils of this miniature relay being the relay coil MR1 responding to the signal received from the control source CS, the other coil MR2, which may be designated the "relay switching coil" functioning, by means of an implementary pressure to alternately "knock-on" and "knock-off" the moving contact 10 as hereinafter explained. That is to say "knock-on" and "knock-off" the positive assistance of the contacts 10 and 20 in both directions of movement. The contacts which are engaged in turn by the moving contact 10 are the contacts 19 and 21, the latter comprising the contact against which is energised in response to the signal from the thermistor 18. The contacts 19 and 21 are a removable contact of the present invention being the contact 20 whilst normally being spaced from the contact 10 and held stationary, is moved into a position ready for engagement by the contact 10 when the "warning on" condition occurs, so that the only period of make between contacts 10 and 20 is a momentary one occurring at the ending of the "warning-on" condition by reason of such making of contacts 10 and 20 shorting out a master relay which serves to maintain the "warning-on" condition. The said master relay is indicated by the reference letter M.

20 It will be seen that the master relay M is connected from the main negative supply lead 1 to the miniature relay coil MR2 through a return hairspring 13 to the moving contact 10. The fixed contact 12 is connected through a resistor R3 (approximately 50 ohms) and a condenser C (which may be 140 μ f.) to the main positive lead 2, and for the displacement of the contact 20 a miniature relay or solenoid shown by way of example as a solenoid S (having a value of about 200 ohms) is included in the miniature or millivolt relay. The main relay M operates normally open contacts 17 in a lead 11 to connect the solenoid S via a lead 3 and a resistor R4 to the positive lead 2, the other side of the solenoid S being connected to negative via lead 9 so that when a signal from source CS closes the contacts 10 and 12 and thereby connects the master relay M to the positive lead 2 through resistor R3 and condenser C, the main relay coil M is energised so as to close contacts 17 thereby energising solenoid S and also transferring the holding current for the relay M via the contacts 17 lead 14, resistor R2, (about 800 ohms) and lead 4. Hence the miniature relay coil MR2 is promptly relieved of the load due to the higher E.M.F. source and the resistor R2 now carries this holding current. The contact 17 also serves to join the positive lead 2 via the lead 11 to a warning lamp 18 or other suitable device to energise it.

25 A further contact 15 is also operated by the master relay coil M and when operated consequent upon energising of the relay M joins the fixed contact 12, via the resistor R3, lead 6 to the main negative lead 1 through

30 hairspring 13, and winding MR2, thus allowing resetting of the circuit. This short circuiting current through coil MR2 is such as to cause implementing pressure, or "knock-on" between contacts 10 and 20 until the master relay M and therefore solenoid S releases when a wiping action takes place between contacts 10 and 20 as contact 20 is displaced from the path of contact 10. Once contact 20 is displaced from the path of contact 10, the current of the source CS is zero or low when the moving contact 10 is in its normal position, i.e. spaced from the contact 20 and no current flows from the higher lead 1. As the voltage from source CS increases the movable contact 10 under the influence of the solenoid S moves towards the fixed contact 12 and immediately they touch, displacement current flows as follows:

35 The main negative lead 1, the master relay coil M, the coil MR2 of the millivolt relay, the hairspring 13, the moving contact 10, the fixed contact 12, the resistor R3, the lead 5, and the condenser C to the main positive lead 2.

40 This displacement charging current through the condenser C is in such a direction through coil MR2 as to cause an implementing pressure which may be termed a "knock-on" pressure between contacts 10 and 12 thus ensuring such a low contact resistance as to obviate sparking across the contacts, and master relay M is energised. Relay M operates its contact 17 in the lead 11 which provides a "holding" circuit, removing the load from the millivolt relay contacts 10 and 12 as follows:

45 50 The main negative lead 1, the relay coil M, the lead 14, the resistor R2, the lead 4, the contact 17 and the lead 11 to the main positive lead 2.

55 At the same time, the movable or armature member of the contact 15 is operated, thus reversing the direction 55 of current through the coil MR2, i.e. providing a "knock-off" current through coil MR2 to separate the contacts 10 and 12 of the millivolt relay. The circuit for this "knock-off" current is as follows:

60 The main negative lead 1, the resistor R7, the contact 15, the lead 6, the resistor R3, the fixed contact 12, the moving contact 10, the hair spring 13, the coil MR2, the lead 14, the resistor R2, the lead 4, the contact 17, and the lead 11 to the main positive lead 2. This reversal of the direction of current through the coil MR2 65 moves the contact 10 away from the contact 12, which momentarily breaks the circuit for this current until, under the influence of the high output from the source CS they are moved together again to remake the circuit. Thus, contacts 10 and 12 make and break continually to ensure that such contacts are readily freed from during the operation of the warning device 18 without shorting out the master relay M and contacting when the output from the source CS is reduced. That is to say as there is intermittent operation of the contact 10 into and out 70 75 of engagement with the contact 12 while the warning de-

vice is on it is not possible for the contacts 10 and 12 to tend to stick together and accordingly immediately the output from the source CS drops due to the extinguishing of a fire outbreak the contact 10 will on its movement away from the contact 12, not return into engagement with the contact 12 but will engage or stop against the contact 20 which will have been displaced to a position for being engaged by the returning contact 10 as hereinafter explained.

Upon the closing of the contact 17 when the relay M is energised, two further circuits are completed, one for the warning lamp 18 from the main positive lead 2, the lead 11, the contact 17, and the lamp 18 to the main negative lead 1, and the other for energising the miniature solenoid S as follows:

The main positive lead 2, the lead 11, the contact 17, the lead 4, the lead 3, the resistor R4, the solenoid coil S, and the lead 9 to the main negative lead 1.

The solenoid S is thus energised, displacing the reset contact 20 into the return path of the movable contact 10 which is still in intermittent contact with the fixed contact 12 due to the high output from source CS. It will be seen that the contact 10 whilst it makes intermittent engagement with the contact 12, cannot engage with the contact 20 during the operation of the warning device, so that the contact 10 moves into engagement with the contact 20 upon reduction in the output of the source CS, hereby ensuring immediately upon touching of the contacts 10 and 20 that the engagement of the contacts 10 and 20 is assisted by the influence of an implementing pressure or "knock-on" current which will flow through the coil MR2 now in series with the contact 20 due to the shorting of the master relay M, this again obviating erratic engagement of the contacts and obviating sparking. The relay M now being de-energised, opens contacts 15 and 17 which subsequently de-energise solenoid S so that the contact 20 is now returned to its normal position completely free of the contact 10. This has a wiping effect between the contacts which prevents accumulation of foreign matter between the engaging faces of the contacts.

The latter described operation ensures a very positive action, and the breaking of the holding contact 17 with consequent de-energising of the solenoid S and displacement of the contact 20 into the neutral position, whereby the moving contact 10 is free to float without contacting the contacts 12 and 20. The making of the contacts 10 and 20 and their subsequent breaking produces a good wiping action to free the contacts of foreign particles, this wiping being most effective due to the tendency of the contact 10 to follow for a short distance of travel the relatively retreating contact 20.

The test button T is provided for testing the apparatus at any time. This button is adapted to connect the resistor R1 to negative lead 1 through relay M via lead 8, and positive lead 2 through a resistor R5 (800 ohms) and lead 27, the resistor R1 being normally short circuited by the fixed contacts 19 and 21 of the test button and in series with the control source CS to coil MR1.

The operation of the test button T is as follows: Normally it bridges the contacts 19 and 21 to short a resistance R1 of about 1 ohm and when making a test the button is depressed to bridge a pair of contacts 24 and 25 to connect the main positive line 2 through a resistance R5 of conveniently about 800 ohms to one side of the resistance R1 via lead 26 and one side of the coil MR1. At the same time, the other side of resistor R1 and one side of the control source CS are connected via lead 16, contacts 22, 23 of T, through lead 8 and relay M to the negative lead 1. This results in applying a very low E.M.F. across the coil MR1, which will initiate operation of the warning device.

The miniature solenoid S is illustrated in FIGURE 2 and comprises the usual coil S¹ in which is located the

usual axially displaceable core S² carrying at one end the contact 20, its other end receiving the inner end of an involute hair spring 13 the other end of which is secured to the end plate or casing of the solenoid and also can receive the lead 9. Behind the solenoid is shown the moving contact 10 and the fixed contact 12, the free end of the moving contact 10 being bent or shaped to ensure it engaging the other two contacts. The casing of the sensitive relay containing the contacts 10, 12 and 20 is indicated at 28.

We claim:

1. In apparatus for giving a warning when there is a sudden high rate of change in temperature, e.g. such as occurs at the outbreak of a fire, which is detected by means responsive to such form of change to produce a low E.M.F. signal, a very sensitive relay operable by said signal; an electrically actuated warning member: a holding circuit operable from a source of E.M.F. much greater than the said signal of low E.M.F. produced by said means and brought in by said very sensitive relay when such relay is actuated by said signal, means with said holding circuit to bring in said warning member, said holding circuit when closed taking the electrical load for keeping in said warning member independently of said relay, said very sensitive relay having first and second contacts and a moving contact normally separated from said first and second contacts and actuated by the said low E.M.F. signal to engage the said first contact to bring in the said holding circuit, said second contact when engaged by the moving contact cutting out the said signal producing means; means producing a "knock-on" implementing pressure between said moving contact and said first contact when the moving contact and said first contact engage an implementary operating when the holding circuit is in to produce an implementing "knock-off" current to said first contact during the continuance of said signal to make and break said moving and first contacts intermittently, said second contact normally being held out of the path of movement of said moving contact, electrically energised means adapted to bring said second contact into said path of movement when the holding circuit is closed to position the said second contact for engagement by the moving contact when the output producing said low E.M.F. signal is reduced and to return said second contact to a normal position out of said path of movement when the holding circuit is broken.

2. Apparatus for giving a warning when there is a sudden high rate of change in temperature, e.g. such as occurs at the outbreak of a fire, comprising means responsive to such form of change to produce a low E.M.F. signal, a very sensitive relay operable by said signal and incorporating a relay coil energised from said low E.M.F. signal and a relay switching coil; a normally cut-out holding circuit served from a source of E.M.F. much greater than the said signal of low E.M.F. produced by said means and brought in by said very sensitive relay when such relay is actuated by said signal, a warning appliance, said very sensitive relay having first and second contacts and a moving contact with resilient means which normally maintains the moving contact separated from said two contacts and also having two separately energised coils to actuate the said moving contact, a normal electrical connection between said low E.M.F. signal producing means and one of said coils to actuate the moving contact by the said low E.M.F. signal to engage the moving contact with said first contact to bring in the said holding circuit and subsequently to engage the said second contact to cut out said holding circuit and restore the apparatus to its normal condition, and electrically energised means to produce relative displacement of the said second contact with respect to said moving contact, said second contact normally being held by said electrically energised means out of the path of movement of said moving contact; a master relay in said holding circuit so as to be energisable from but normally isolated

from said greater E.M.F. source and connectable to said greater E.M.F. source via said moving contact and said first contact; contact means closed and opened by the energising and de-energising of said master relay and when closed bringing in said electrically energised means and said holding circuit and warning appliance when the said low E.M.F. signal is put out by said low E.M.F. source to displace said second contact into the path of free movement of said movable contact, so as to be engaged by the said movable contact when the said low E.M.F. output is reduced, means to supply implementary "knock-on" current charge to said relay switching coil when said master relay is brought into circuit to implement the pressure of the moving contact against said first contact and when said signal disappears to produce a momentary "knock-on" action between said moving contact and said second contact and the shorting of said master relay and de-energising of said electrically energised means to restore the apparatus to normal condition.

3. Apparatus for giving a signal of a sudden high rate of change of temperature, e.g. such as occurs on the outbreak of fire at a control source, comprising thermo-couple means adapted to produce a low voltage signal consequent upon a sudden rise in temperature at said source; a first circuit including and deriving low voltage current from said thermo-couple means; a sensitive two-coil relay having a first "fixed" contact and a second contact and a "movable" contact normally separated from said first and second contacts and engageable with said first contact when said low voltage current is developed in one direction through one of the coils of said two-coil relay, said latter one coil being in series connection with the said thermo-couple means in said first circuit, electrically operated warning means; a second circuit provided through the other one of the coils of said relay and when closed served from a source of continuous voltage and adapted when closed to maintain said electrically operated warning means connected to said source of continuous voltage; said second circuit being normally inoperative but being completed on engagement of said "movable" contact with the said first contact of said relay and maintained completed independently of said relay; and electrically energised actuator operatively connected to said second contact and included in said second circuit and energised as the result of the completion of such second circuit and when energised serving to displace said second contact into a position ready for engagement by the said "movable" contact of the sensitive two-coil relay when the current from the thermo-couple means drops to cause upon said latter engagement shorting out of the said actuator and the returning of the second contact to an idle or "free" position clear of the said "movable" contact.

4. Apparatus according to claim 3 including a condenser between said source of continuous voltage and said first contact of the two-coil relay and adapted by reason of the direction of displacement charging current therethrough relative to the said other one of the coils of said relay as to cause an implementary pressure between said "movable" contact and said first contact of the relay upon engagement of such contacts.

5. Apparatus for giving a signal of a sudden high rate of change of temperature, e.g. such as occurs on the outbreak of fire at a control source, comprising thermo-couple means adapted to produce a low voltage signal consequent upon a sudden rise in temperature at said source; a first circuit including and deriving low voltage current from said thermo-couple means; a sensitive two-coil relay having a first "fixed" contact and a second contact and a "movable" contact normally separated from said first and second contacts and engageable with said first contact when said low voltage current is developed in one

direction through one of the coils of said two-coil relay, said latter one coil being in series connection with the said thermo-couple means in said first circuit, electrically operated warning means; a second circuit provided through the other one of the coils of said relay and when closed served from a source of continuous voltage and adapted when closed to maintain said electrically operated warning means connected to said source of continuous voltage; said second circuit being normally inoperative but being completed on engagement of said "movable" contact with the said first contact of said relay and maintained completed independently of said relay; an electrically energised actuator operatively connected to said second contact and included in said second circuit and energised as the result of the completion of such second circuit and when energised serving to displace said second contact into a position ready for engagement by the said "movable" contact of the sensitive two-coil relay when the current from the thermo-couple means drops to cause upon said latter engagement shorting out of the said actuator and the returning of the second contact to an idle or "free" position clear of the said "movable" contact, and a manually operable switch; a first resistor and a second resistor of higher value than the first resistor, said switch normally shorting said first resistor, said first resistor being connected across the control source and the first coil of the sensitive relay, said switch being actuatable to connect the higher source of E.M.F. to the said first coil of the sensitive relay via said first resistor and said second resistor to introduce a test signal into the apparatus.

6. Apparatus for giving a warning when there is a sudden high rate of change in temperature, e.g. such as occurs at the outbreak of fire, a thermo-couple assembly to detect such form of change to produce a low E.M.F. signal, a very sensitive relay operable by said signal; a normally cut-out electrically operated warning appliance; a normally cut-out holding circuit served from a source of continuous voltage and adapted when closed to connect said warning appliance to said source of continuous voltage; a master relay to bring in said holding circuit and warning appliance and controlled by said very sensitive relay when such very sensitive relay is actuated by said signal; said master relay being served from said source of continuous voltage; said very sensitive relay having first and second contacts and a moving contact normally separated from said two contacts and actuated by the said low E.M.F. signal to engage the said first one of the contacts to bring in the said master relay to close the holding circuit and subsequently to engage the second one of said contacts to cut out said master relay and holding circuit and restore the apparatus to its normal condition; an electrically energisable actuator normally deenergised to hold said second contact out of the path of movement of said moving contact and adapted when energised to apply displacement to said second contact into the path of free movement of said movable contact, said actuator being connectable for energising to said continuous voltage source in common with said warning appliance.
